UNITED STATES PATENT OFFICE.

JOSEPH L. LYNCH, OF MCKEESPORT, PENNSYLVANIA.

TIE-PLATE.

1,125,854.

Specification of Letters Patent.

Patented Jan. 19, 1915.

Application filed January 16, 1914. Serial No. 812,480.

To all whom it may concern:

Be it known that I, JOSEPH L. LYNCH, a citizen of the United States, residing at McKeesport, in the county of Allegheny, State of Pennsylvania, have invented certain new and useful Improvements in Tie-Plates; and I do hereby declare the following to be a full, clear, and exact description of the invention, such as will enable others skilled in the art to which it appertains to make and use the same.

This invention relates to new and useful improvements in metal ware plates for railway ties and has particular reference to the provision of such plates provided with means preventing relative movement of the plate to the tie.

The object of the present invention resides in the provision of a tie plate of the class described which is provided with means preventing the rail from creeping forward, when a train is moving thereover with its brakes applied, or creeping backward when an engine positioned thereon is starting a heavy load.

A further object of the invention resides in the provision of such a tie plate which may be readily associated with relation to a tie and rail and which is of such simple construction as to conduce to economical manufacture.

With these and other objects in view, the invention resides in the novel combination, formation and arrangement of parts to be more fully hereinafter described and illustrated in the accompanying drawings and particularly pointed out in the claim here-to appended.

Reference is had to the accompanying drawings wherein similar characters of reference designate corresponding parts throughout the several views, and in which:

Figure 1 is a side elevational view of the plate in attached position, showing the rail in cross section, Fig. 2 is a top plan view of what is shown in Fig. 1, Fig. 3 is a perspective view of the plate and Fig. 4 is a bottom plan view of the plate.

Referring now more particularly to the accompanying drawings, 5 designates a railway tie of any desired material and 6 designates the improved tie plate which is held thereon by the screws 7 or other suitable retaining means. To relieve the shearing

strain which would ordinarily come upon the retaining means by a tendency of the plate to move transversely or longitudinally of the tie, the plate is provided on its under face with a pair of spaced ribs 8 extending transversely of the tie and firmly engaging the same and the plate is also provided on its bottom face with a Z-shaped rib 9 having its parallel portions disposed between and at right angles to the ribs 8. To lighten the construction of the plate, the top face thereof is provided with a plurality of transverse grooves 10.

The rail 11 is positioned on the top face of the plate and within a seat formed by the transversely extending upstanding ribs 12. To prevent creeping of the rail with relation to the plate, the side portions of the rail are provided with recesses 13 and the plate is provided inwardly of the ribs with projections 14 forming shoulders against which the ends of the recess abut. The usual retaining spikes 15 are passed through the projections 14.

It is thus seen that the rail is firmly held against creeping, as the plate is held against creeping movement with relation to the tie which is firmly embedded and the rail is held against movement with relation to the plate. A very simple structure is thus provided which will efficiently perform all of the functions normally required thereof.

What is claimed is:

A tie plate comprising, in combination with a tie and rail, a body portion positioned on the tie, a pair of spaced ribs formed on the lower side of said body portion and extending transversely of the tie, a Z-shaped rib formed on the under side of said body portion and having its parallel portions disposed at right angles to said ribs, said ribs serving to bite into the tie and prevent longitudinal movement and lateral movement of said body portion thereon, and means on said body portion for engagement with the base of a rail whereby said rail will be prevented from movement on said body portion.

In testimony whereof, I affix my signature, in the presence of two witnesses.

J. L. LYNCH.
